HEADREST

Ardis M. Thoma, Los Angeles, Calif.

Application January 31, 1950, Serial No. 141,423

3 Claims. (Cl. 155—174)

1

The present invention relates to improvements in headrests. It is intended in particular for attachment to the back of seats in buses and trains to support a passenger's head and reduce annoying noises.

An object of the invention is to provide a headrest that is designed to closely confine the sides of a person's head, and at the same time hold the head of the user comfortably in place. When in use, the headrest will restrain forward and lateral movement of the person's head, while asleep, or upon sudden deceleration of the vehicle. At the same time the cushions of the headrest fit over the person's ears, thus substantially precluding noise from annoying the passenger.

Moreover, I propose to provide a headrest having head-embracing cushions, which may be adjusted with facility and ease to accommodate the rest to different head sizes.

Other objects and advantages will appear as the specification proceeds, and the novel features of the invention will be set forth in the claims hereunto appended.

Drawing

For a better understanding of the invention, reference should be had to the accompanying drawing, forming part of this invention, in which:

Figure 1 is a top plan view of my headrest with the cushions thereof embracing opposing sides of a person's head: and

Figure 2 is a vertical sectional view taken along the plane II-II of Figure 1.

While I have shown only the preferred form of my invention, it should be understood that various changes, or modifications, may be made within the scope of the annexed claims without departing from the spirit thereof.

Detailed description

Referring to the drawing in detail, I have disclosed a pair of cushions indicated generally at A, which are arranged in spaced-apart relation with one another for the reception of a person's head B therebetween.

These cushions are mounted on a band C that is designed to encircle the back D of a seat in a bus, train, or the like. As the specification continues, it will be clear that the band C may be adjusted with respect to the back D so that the cushions A will embrace opposite sides of the person's head and cover the latter's ears.

The band C provides reaches 10 and 11, which 55

55 The full line position of the pads in Figure 1

show them flexed to present slightly concaved surfaces 17b overlying the person's ears. In other words, the resilient pads are compressed during the insertion of the head. Upon withdrawing the head, the pads will bulge toward one another and assume their extended positions shown by the dot-dash lines in Figure 1.

Moreover, it will be seen that the cushions A are disposed on opposite sides of the adjustable connection 14. Accordingly, the latter may be changed to move the cushions toward and away from one another to accommodate the head size of the user. Inasmuch as the soft pads 17 are not attached directly to the reach 10 of the band C, they may be flexed to permit easy introduction of the person's head therebetween. However, the semi-rigid bases 16 will give the pads sufficient support or backing to hold them in operative position.

Summary of operation.

The operation of my headrest is summarized briefly as follows:

As the first step, the band C is placed around the back D of the chair or seat at the proper elevation thereon to present the cushions A in a position for embracing the person's head B. The buckle 15, or other fastening means, is tightened so as to retain the band in place. The adjustable fasteners 14 are attached together to give the desired spacing between the resilient pads 17 for a comfortable insertion of the person's head, while at the same time providing a mild clamping action on the introduced head.

With the person sitting in the chair or seat, the user's head is moved rearwardly between the tips 17a of the resilient pads. The latter will yield, allowing the head to be moved against the reach 10 of the band C. The resilient pads urge the head rearwardly when it is in position, and will closely confine the head. There will be a tendency for forward movement of the head to be restrained. Of course, the pads will restrain lateral rolling of the user's head. However, limited movement of the head is provided, although the head is not clamped rigidly in position.

I claim:

1. In a headrest of the character described: a band providing reaches designed to extend across front and rear surfaces, respectively, of a seat back; a pair of triangularly-shaped bases disposed in spaced-apart relation with one another; each base having one side thereof secured to the front reach of the band; the bases defining inclined sides converging relatively to one another in a direction toward the front reach of the band; and resilient pads secured to said inclined sides of the bases and projecting toward one another and away from the front reach of the band to embrace opposite sides of a person's head introduced therebetween.
2. The combination defined in claim 1, in which, the pads are made of soft sponge-rubber.
3. In a headrest of the character described: a band providing reaches designed to extend across the front and the rear surfaces, respectively, of a seat back; a pair of cushions having base portions disposed in spaced-apart relation with one another and secured to the front reach of the band; the outer ends of the cushions projecting toward each other and away from the front reach of the band to embrace opposite sides of a person's head introduced therebetween; the base portions of the cushions being disposed farther apart than the outer ends so as to give freedom to the back of the head and neck of the person for air to flow thereby.
